CHILD'S TOY

Dolores Drucker, Cincinnati, Ohio, assignor to Dolores, Cincinnati, Ohio, a partnership composed of Dolores Drucker and Bernard Cassell

Application June 19, 1948, Serial No. 147,081

Term of patent 14 years

(Cl. D34—15)

To all whom it may concern:

Be it known that I, Dolores Drucker, a citizen of the United States, residing at Cincinnati, in the county of Hamilton and State of Ohio, have invented a new, original, and ornamental Design for a Child's Toy, of which the following is a specification, reference being had to the accompanying drawings, forming a part thereof.

The single figure is a perspective view of a child's toy, showing my new design.

I claim:

The ornamental design for a child's toy, as shown.

DOLORES DRUCKER.
